ATTORNEY

UNITED STATES PATENT OFFICE.

JAMES R. MCWANE, OF BIRMINGHAM, ALABAMA.

MOLDING FLASK.

Original application filed May 12, 1923, Serial No. 638,639. Divided and this application filed August 25, 1924. Serial No. 734,002.

To all whom it may concern:

Be it known that I, JAMES R. MCWANE, a citizen of the United States, residing at Birmingham, in the county of Jefferson and State of Alabama, have invented new and useful Improvements in Molding Flasks, of which the following is a specification.

This invention relates to flasks for molding purposes, and the present application is 10 a division of an application for patent filed by me May 12, 1923, on a pipe foundry plant, Serial No. 638,639.

The object of the present invention is to improve the construction of flasks used in 15 the manufacture of cast iron pipe or other analogous articles of elongated form, in order to facilitate handling of the same by over-head, power-driven hoisting means, used in pipe foundries.

20 Another object is to provide means at each end of each cope and drag section or member of the flask, whereby a quick and safe hitch may be made to the said hoisting means to pick up and move said members in the process of molding and "shaking out," and to enable the drags to be inverted, while suspended by the hoisting means, without interference with or entangling the latter.

25 A full and complete understanding of the invention may be obtained from a consideration of the following detailed description, taken in connection with the accompanying drawing forming a part of this specification, it being understood that while the drawing 30 shows a practical form of the invention, the latter is not to be confined to strict conformity with the showing thereof, but may be changed or modified, so long as such changes or modifications mark no material 35 departure from the salient features of the invention, as specifically pointed out in the appended claims.

40 In the drawing, in which similar reference characters designate corresponding parts 45 throughout the several figures—

Figure 1 is a plan view of a flask comprising cope and drag members equipped with the present improvements;

Figure 2 is a side elevation of the upper or 50 cope member of the flask; and

Figure 3 is an end view of the same, the lower or drag member being indicated in dotted lines.

The drawing illustrates a flask in use in

the manufacture of cast iron pipe, the same 55 consisting of two oppositely disposed members fitted together and having the proper sand mold formed therein, the two members being, of course, separable in order to form such mold and to remove the pipe or other 60 article after casting, it being understood that the improvements are applicable to flasks of other kinds and for producing articles other than cast iron pipe.

In Figure 1 the uppermost member of the 65 flask, known as the cope 1, is shown of elongated form and consisting of a hollow, cast metal shell, open on its under or wide side, and also open on the top, and having enlarged ends 2 so as to provide space at either 70 end for forming the bell end of the pipe. The illustrated flask is designed for use in connection with the multiple-lipped pouring ladle disclosed in the aforesaid application, which necessitates the provision of the plurality of pouring openings or gates 3, as shown in said Figure 1, there being preferably, a division plate 4 placed in the sand midway between each gate 3, all of which, however, is not concerned with the present 75 invention, as the latter may be applied to any other form of flask.

As shown in Figure 3, each of the flask members, that is to say, the cope 1 and the drag 5 (shown in dotted lines), is provided with side walls 6 having a double inclination, so that each has a relatively wide top 7 and a narrow bottom 8, which formation reduces the quantity of sand necessary and facilitates nesting or stacking the copes and drags, the narrow bottoms being placed within the open top of the member below, as will be readily understood.

90 Each cope and drag is provided, at each end, with a pair of lugs or trunnions, formed integrally therewith, or otherwise secured to the same and extending longitudinally thereof. The trunnions 9, one at each end, are in longitudinal alinement with each other and located adjacent to one inclined side wall 6, as shown in Figure 1, the said pair of trunnions being also in the same horizontal plane with each other and adjacent to the wide top 7. The other pair of trunnions 10 are located in the same relative position to the other inclined side wall of the member, and in a horizontal plane 95 with the trunnions 9, and all of the trun-

nions are provided with a circumferential groove 11 adjacent to their outer ends.

The trunnions 9 are considerably longer than the trunnions 10, and the grooves there-
5 of are located beyond the ends of the latter, and they are so located with relation to the entire flask section, that the latter may be conveniently handled and transported from the molding machine to the pouring floor,
10 without disturbing the sand therein, when the cables or falls from the aforesaid hoisting means have been hooked or connected to the grooves in the several trunnions. The said cables or falls are preferably formed of
15 a single length, having their ends formed into loops to engage the trunnions, and having the intermediate portion thereof passed over a sheave suspended at each end of a spreader bar, which, in turn, is adapted
20 to be elevated by a travelling hoist.

The prime object in the provision of the long and the short trunnions 9 and 10 respectively, is to permit the copes and the drags to be inverted while being held by the
25 overhead supporting cables or falls, without the necessity for separate supporting means, and without disengaging the same from the cables. It will be seen that the grooves 11 of the longer trunnions 9, being a greater
30 distance apart, will cause the supporting cables or falls connected thereto to pass on the outside of the corresponding cables or falls connected to the short trunnions, as the flask section is rocked or turned about its
35 longitudinal axis. This rocking or turning action may be accomplished by hand, as it is only necessary to lift one longitudinal half

of the said section. This turning action is necessary in the case of the lower or drag section, in order to invert the same in sus-
40 pension after it is lifted off the molding machine.

From the foregoing it will be seen that a simple means has been provided for sup-
45 porting flask sections or other analogous members and permitting the same to be in-
verted, while under suspension, the said means being easily formed with the said sec-
tion or applied thereto, and in no way inter-
fering with the stacking or nesting or other-
50 wise handling the same.

What is claimed is:—

1. A flask section having two pairs of alined trunnions, one pair being longer than the other.

2. A flask section having two trunnions at each end, one of the two trunnions being longer than the other.

3. A flask section having opposite pairs of longitudinally-alined trunnions, the trunnions of each pair being located at opposite ends of said section, and the trunnions of one pair being correspondingly longer than the trunnions of the other pair.

4. A flask section having two pairs of alined trunnions, one pair being longer than the other, each of said trunnions having a circumferential groove adjacent to the free, outer end thereof.

In testimony, that I claim the foregoing as my own, I have hereto affixed my signature.

JAMES R. McWANE.
